UNITED STATES PATENT OFFICE.

CHARLES L. HEISLER, OF ERIE, PENNSYLVANIA.

PUMPING-ENGINE.

No. 853,359.

Specification of Letters Patent.

Patented May 14, 1907.

Application filed April 4, 1902. Serial No. 101,334.

To all whom it may concern:

Be it known that I, CHARLES L. HEISLER, a citizen of the United States, and a resident of Erie, in the county of Erie and State of Pennsylvania, have invented certain new and useful Improvements in Compensating High-Duty Pumping-Engines, of which the following is a specification.

My invention relates to improvements in high duty compensating pumping engines, in which a system of compensating levers connect the pair of reciprocating piston or plunger rods, in such a manner as to form a substitute for a fly wheel, and which fix the motion or strokes of the reciprocating piston rods relatively with each other.

The purpose of the invention is to provide an automatic starting and regulating device attached to the pumping engine in such a manner as to maintain the proper proportion of power developed in the steam cylinder or cylinders attached to one of the reciprocating plunger or piston rods, as compared with the power exerted by the steam acting on the other reciprocating rod; thereby producing a more uniform and quiet action, and materially lessening the stress upon the compensating system of levers.

Figure 1 shows a general arrangement of the compensating system and application of the automatic valve on the steam cylinders. Fig. 2 shows a cross section of the automatic valve when flexible metallic diaphragms of different areas are used instead of movable pistons as shown in Fig. 3. Fig. 4 shows a top outside view of the cross section in Fig. 2. Fig. 5 shows a detail of the valve. Fig. 6 shows a general top view of the engine.

The valve accomplishes its object by automatically by-passing steam from one side of the engine having the higher steam pressure to the other, so that the pressures will be maintained in the proper proportion relatively; thereby causing the requisite amount of work to be done on either side, as may be necessary for quiet and uniform action.

The valves shown in Figs. 2 and 3 are identical, excepting that in Fig. 3, the diaphragms 1 and 2 are different in form. The steam from the high pressure steam chest 3, forming part of the cylinder 12, and attached to the right hand rod 13, enters the chamber 4 containing the smaller diaphragm 1. A valve 5 intercepts a port 6 in the diaphragm,

which leads to the larger diaphragm chamber 7, and from there to a receiver 8 or steam chest 9 of the cylinder 10 attached to the left piston rod 11. The space 14 between the diaphragms may be open to the atmosphere.

By proportioning the areas of the diaphragms to suit the cylinder ratios, the desired reduction of pressure may be obtained, which may be further adjusted by means of the threaded valve stem 15. The springs 16 and 17 acting to increase or decrease the amount of difference in pressure necessary to move the diaphragms and open the valve 5. Between the valve 5 and its seat 18 is placed a ball ring 19, so constructed that the valve 5 will close tightly in case it is not fair with the seat. Suitable means for retaining the ball ring in its proper place is provided by the lugs 20. A spring 21, acting against the ball ring 19, prevents it chattering when steam passes through the valve. A stop valve 22 is arranged between the automatic valve and one of the cylinders, so the latter may be cut out when necessary.

When starting the engine, steam is admitted into the high pressure steam chest, then because of the difference of pressure, steam passes into the low pressure side and gives the necessary pressure for a starting.

Evidently, the invention is not limited in its application to the particular compensating linkage shown, but may be applied to similar compensating engines.

Having fully described my invention, I claim as follows:

1. In a direct acting pumping engine, the combination of compound steam cylinders connected to a duplex pump end, a compensating lever system connecting the pair of reciprocating plunger or piston rods, and an automatic steam valve intercepting a steam passage between a steam chest or receiver on one side, and a steam chest or receiver on the other side, having a lower steam pressure, the said valves having a pair of diaphragms or pistons of different area, a valve actuated by said pistons or diaphragms conjointly, and an adjustable valve opening arranged upon said diaphragms.

2. In a direct acting pumping engine, the combination of compound steam cylinders connected to a duplex pump end, a compensating lever system connecting the pair of reciprocating plunger or piston rods, and an

automatic steam valve intercepting a steam passage between a steam chest or receiver on one side, and a steam chest or receiver on the other side, having a lower steam pressure, 5 the said valve having a pair of diaphragms or pistons of different areas, a valve actuated by said pistons or diaphragms conjointly, an auxiliary stop valve interposed between

the said automatic valve and one of the steam cylinders.

In testimony whereof I sign my name to hereunto.

CHARLES L. HEISLER.
